(57) **CLAIM**

I claim the ornamental design for a industrial glove, as shown and described.

DESCRIPTION

FIG. 1 is a front view of a industrial glove;

FIG. 2 is a perspective view of FIG. 1; and,

FIG. 3 is a partially enlarged view of a palm portion side view of FIG. 1.

The broken line showing on the industrial glove are included for the purpose of illustrating environmental structure and forms no part of the claimed design.

1 Claim, 3 Drawing Sheets

FIG. 1

FIG. 2

FIG. 3
